UNITED STATES PATENT OFFICE.

JOSEPH C. STINE, OF OSCEOLA MILLS, PENNSYLVANIA.

POWER-FAN.

No. 874,805.

Specification of Letters Patent.

Patented Dec. 24, 1907.

Application filed January 21, 1907. Serial No. 353,272.

To all whom it may concern:

Be it known that I, JOSEPH C. STINE, of Osceola Mills, in the county of Clearfield, State of Pennsylvania, have invented certain new and useful Improvements in Power-Fans, of which the following is a specification.

The object of my invention is to produce improvements in power fans for the ventilation of mines, for example, or similar purposes.

Fans of the class referred to are necessarily of large dimensions to accommodate them to the work required of them, the diameter of the fans proper ranging from say five feet to sixteen feet.

In fans of the class and size suggested, particularly when running at a high rate of speed, the strain upon the vanes is a heavy one requiring special provision to be made to protect the vanes from shearing away the bolts, or similar means for securing the vanes to their hub. It is with this fact in view that my invention is to provide improved and secure means for attaching the vanes of a fan to its hub.

In the accompanying drawing, which constitutes a part of this application, Figure I is a perspective view of a fan embodying my invention. Fig. II is an elevation of the fan proper, shown in Fig. I and detached from its supporting and actuating mechanism. Fig. III is a perspective view showing a portion of a vane, axial support, and shaft embodying my invention. Fig. IV is a perspective view of the vane and hub connecting member.

Referring to the numerals on the drawing, 1 indicates the bed-plate of my fan; upon which is carried a bench 2 for the support of a motor 3, geared to a shaft 4 that is carried in suitable bearings on supporting-members 6 and 7 arranged upon opposite sides of a casing 8, the supporting-member 6 being, for compactness of assemblage, mounted upon the top of the bench 2, upon which it is bolted. Upon the shaft 4, within the casing 8, is carried the fan proper, which consists of a series of vanes 10, a wheel or hub 11, and braces 12.

My invention consists in improved means of attaching the vanes to the wheel or hub, and comprehends essentially a projection 15, fitted and countersunk into one of a series of

recesses 16, preferably radial, angular in cross section; and upon one side of the hub, of which one is provided in the wheel or hub 11 for each vane comprised in the fan proper. The projection 15, being snugly fitted and countersunk into its recess 16, may be secured by a series of screws 17. The office of the screws is to hold the vane snugly into position but not to receive any shearing strain from the drive of the vane through the air when the fan is in motion. On the contrary, all such strain spends itself against the side walls of the recess. By this arrangement, a strong, rugged, durable, and rigid construction is arrived at.

I prefer to make the projection 15 a part of a vane and hub uniting member, shown in detail in Fig. IV. It consists of the projection 15 and a vane-plate 18, the two being integrally united by an intermediate bend or shoulder 19. The shoulder 19 may be made of triangular shape so as to impart a cant to the plate 18 with respect to the projection 15, thereby lending to the vane, which, as by bolts or rivets 20, is secured to the vane-plate 18, the desired inclination.

What I claim is:

1. In a power fan, the combination with a hub provided with a series of radial recesses, of vanes disposed about said hub as an axis, and a vane and hub uniting member for each vane, consisting of a projection upon one end, fitting within a recess in the hub, and a plate upon the other end secured to the vane, and an intermediate shoulder, whereby the desired inclination with respect to the hub may be imparted to the vane.

2. In a power fan, the combination with a hub provided with a series of radial angular recesses, of vanes disposed about said hub as an axis, and a vane-and-hub-uniting-member for each vane comprising a projection, an intermediate shoulder, and a plate, said projection and intermediate shoulder fitting within a recess in the hub, and said plate being secured to the vane, substantially as described.

In testimony whereof I have hereunto signed my name in the presence of two subscribing witnesses.

JOSEPH C. STINE.
